CLAIM

The ornamental design for covered electrical inlet housing, as shown and described.

DESCRIPTION

FIG. 1 is a perspective view of a covered electrical inlet housing showing my design;

FIG. 2 is a top plan view thereof;

FIG. 3 is a front elevation view thereof;

FIG. 4 is a rear elevation view thereof;

FIG. 5 is a right side elevation view thereof, the left side elevation view thereof being a mirror image; and,

FIG. 6 is a bottom view thereof.
